UNITED STATES PATENT OFFICE.

ARTHUR W. NELSON, OF WILLIAMSPORT, PENNSYLVANIA, ASSIGNOR TO HERMANE MACHINE COMPANY, OF WILLIAMSPORT, PENNSYLVANIA, A CORPORATION OF PENNSYLVANIA.

PLANING-MACHINE.

1,111,702.

Specification of Letters Patent.

Patented Sept. 22, 1914.

Application filed April 28, 1913. Serial No. 764,112.

To all whom it may concern:

Be it known that I, ARTHUR W. NELSON, a citizen of the United States of America, residing at Williamsport, in the county of 5 Lycoming and State of Pennsylvania, have invented certain new and useful Improvements in Planing-Machines, of which the following is a specification, reference being had therein to the accompanying drawings.

10 My invention relates to feed mechanism of planing machines and has among the objects thereof to provide a novel construction whereby the coöperating feed rolls may be readily separated so as to permit the work 15 to be inserted therebetween or withdrawn therefrom; to provide such a means which will also serve to retain the rolls in the desired spaced relation and will permit this spaced relation to be readily varied; and 20 further to provide a construction which will move the chip breaker away from the bed upon the separation of the feed rolls.

The invention resides in the peculiar construction, arrangement and combination of 25 parts as will more fully hereinafter appear and as claimed.

In the drawings,—Figure 1 is a fragmentary plan view of a machine embodying my invention; and Fig. 2 is a side elevation, 30 partly in section.

A designates the bed of the machine; B a cutter head—herein shown as arranged above the bed A—and C is the chip breaker, positioned in advance of the cutter head.

35 D E and F G are coöperating pairs of feed rolls.

One member of each pair of feed rolls, as the upper members D F, are mounted so as to be moved away from the members E G. 40 Thus the member D is attached to a shaft D' journaled in a sleeve D² of an arm H, mounted for rocking movement upon a pivot I, while the shaft F' of the member F is journaled in the sleeve F² of an arm J, 45 fulcrumed at K to a portion of the frame. The members D F are normally pressed toward the rolls E G by a weighted arm L in the usual manner, and movement of the rolls D F toward their coöperating members 50 is limited by means of a slide M having cams or inclines N O engaging the sleeves D² F². The slide M is adapted to be longitudinally shifted through the medium of a lever P fulcrumed at Q for movement in a

horizontal plane upon the frame of the machine and secured to the slide by means of a link R having its opposite ends pivotally connected to the lever and the slide. Thus upon shifting of the lever P in one direction the slide is adjusted rearwardly, or to 55 the position shown in dotted lines in Fig. 2, thereby raising the bearings D² F² and separating the feed rolls. When the lever is moved in the opposite direction, the slide M will be adjusted inwardly. Inward movement of the slide however, is limited by means of a set-screw S on an extension T of the slide. By adjusting the screw S the normal spaced relation of the coöperating feed rolls may be varied as desired. It is also 60 65 advisable to so mount the chip breaker that upon the separation of the feed rolls the chip breaker will be moved away from the bed. This is accomplished by providing an arm U which is secured at one end to the 70 chip breaker and carries at its opposite end a screw V adapted to rest upon the sleeve D². The chip breaker is also mounted upon a rockable arm as W and therefore, upon the raising of the sleeve D² the chip breaker 75 80 will be correspondingly adjustable. Preferably the length of the screw V may be adjusted so as to properly position the same in relation to the feed rolls and to the bed.

What I claim as my invention is:— 85

1. In a planing machine, the combination with a plurality of pairs of feed rolls, the members of each pair being respectively positioned upon opposite sides of the line of feed, rockable means carrying one member 90 of each pair upon the same side of the line of feed, a shiftable slide adapted to rock said means to move the rolls carried thereby away from their coöperating members, said slide serving to maintain the rolls in 95 normal spaced relation, an extension on said slide, means for limiting the inward movement of said extension, a lever pivoted for movement in a horizontal plane and connected to said slide to effect the shifting 100 thereof, and means for varying the relation of the slide to said rockable means to adjust the normal spaced relation of the feed rolls.

2. In a planing machine, the combination 105 with a pair of feed rolls positioned upon opposite sides of the line of feed, of a rockable support for one of said rolls permitting

the same to be moved away from the other, a second rockable support partially extending over said first-mentioned support, an adjustable screw arranged in said portion over said support adapted to rest upon said first-mentioned support, a chip-breaker upon the second rockable support, and means for simultaneously adjusting said movable roll

and said chip-breaker away from the line of feed.

10

In testimony whereof I affix my signature in presence of two witnesses.

ARTHUR W. NELSON.
